MUFFLE FLUE

Charles W. Saxe, Worcester, Mass., assignor to
 Norton Company, Worcester, Mass., a corporation of Massachusetts

Application March 10, 1936, Serial No. 68,082

2 Claims. (Cl. 263—42)

The invention relates to kilns and furnaces, and more especially tunnel kilns, and with regard to its more specific features to a muffle flue therefor.

5 One object of the invention is to provide a muffle flue construction of high efficiency so far as heat transference is concerned and of a readily manufactured construction. Another object of the invention is to provide a muffle flue assembled 10 from plates which may be of great density. Another object of the invention is to provide an inexpensive construction for a muffle flue. Other objects will be in part obvious or in part pointed out hereinafter.

15 The invention accordingly consists in the features of construction, combinations of elements, and arrangements of parts, as will be exemplified in the structure to be hereinafter described, and the scope of the application of which will be indicated in the following claims.

In the accompanying drawing in which is shown one of many possible embodiments of the invention,

Fig. 1 is a transverse sectional view of a tunnel kiln having incorporated in it two muffle flues according to my invention;

Fig. 2 is a side elevation of a plate for my muffle flue;

Fig. 3 is a longitudinal sectional view taken on the line 3—3 of Fig. 2;

Fig. 4 is a bottom view of the plate of Fig. 2;

Fig. 5 is an end view of the plate of Fig. 2;

Fig. 6 is a transverse sectional view taken on the line 6—6 of Fig. 2;

35 Fig. 7 is a transverse sectional view taken on the line 7—7 of Fig. 2;

Fig. 8 is a side elevation of the T used to attach two plates together in constructing my muffle flue;

40 Fig. 9 is a cross sectional view taken on the line 9—9 of Fig. 8 and showing two plates in position in the T;

Fig. 10 is a view similar to Fig. 9 but taken on the line 10—10 of Fig. 8;

45 Fig. 11 is a bottom view of the T, looking along lines parallel to elements of a plate.

Referring now to Fig. 1, a tunnel kiln may comprise a floor 20, a pair of rails 21, 21 forming a track for a car 22 having wheels 23, the car 50 22 being located between massive supports 24, 24 formed of firebrick and providing ledges 25, 25 whose surfaces are in a common horizontal plane for the support of the muffle flues 26, 26 of the invention. The ware chamber 27 is bounded by 55 side walls 28, 28 of firebrick, and an arch 29 also

of firebrick, and suitable seals 30, 30 comprising depending members attached to the car 22 and extending into troughs 31, 31 which are filled with sand is preferably provided to insulate the ware chamber 27 from the chamber 32 in which are the tracks 21 and the running gear of the car 22. The ware 33 is piled upon the car 22 which travels slowly through the kiln, the cross section of Fig. 1 being more or less typical of the entire length of the kiln. Combustion gases 5 are generated in any known or desired manner and passed along and through the triangular flues 26 of the invention, ultimately emerging and passing through passages to stacks, not shown. Tunnel kilns are already known and the flue of the invention may be utilized in any desired type of tunnel kiln, the type briefly described being illustrative.

Considering now the construction of the flues 26, I provide a number of identical plates 35. 20 Fig. 3 shows a longitudinal section of the plate 35 which is shown in elevation in Fig. 2; the section is uniform along the entire transverse extent of each plate 35 between the dotted lines shown in Fig. 2. Figs. 5, 6 and 7 are end and 25 transverse sectional views of the plate 35 and Figs. 2 to 7 inclusive quite definitely establish the shape and configuration of the plates. It will be seen that they are corrugated and furthermore that one plate can be matched to another plate to make a corrugated wall of indefinite extent. Furthermore, they are bevelled as shown.

I provide T shaped unions 40, as shown in 35 Figs. 8, 9, 10 and 11. I provide as many T members 40 as there are plates 35. Each T comprises a top portion 41, two similar side portions 42, and a vertical portion 43. The under side of the portions 42 has a corrugated boundary, as shown in Figs. 8 and 11. Plates 35 fit between portions 42 and 43 as fully illustrated in the several views, particularly Figs. 9 and 10.

Three plates 35 and three T's 40 are assembled together in the manner shown in Fig. 1. 45 A plate 35 is first laid flat with the bevelled edges 45 uppermost, and two T's 40 are then moved into engaging position with this plate, the bottom side of the portions 42 being horizontal, as shown. The parts may be readily put together and cement may be laid in the unions. Two more plates are now inserted at 60° to each other and to the first plate to complete the triangle. The top T 41 may be slipped into position after the two side plates 35 are inserted in the two bottom T's 41. The fit of the plates in the 50 55

T's is preferably slightly loose so that a slight angular motion of the plates is permitted. This is in order to prevent breakage of the parts. The space left by this loose fit is filled with a suitable cement in order tightly to seal the unions.

I may form sections of the muffle flue as indicated and then abut them and cement them together. On the other hand, I may provide a couple of plates of exactly one-half the length 10 of the plates 35 and interlock these with full length T's 40; this will leave a space in the T's and I may then interlock full length plates 35 with these same T's. This will leave one-half 15 of the length of the plates 35 extending beyond the T's, and I may then interlock these plates with additional full length T's which will leave the T's but half filled with plates. I may then use full length plates which will then extend beyond these T's, and so on, finishing up with 20 half length plates 35. Thus the entire structure will be rigidly locked together.

For the manufacture of the plates and also the T's, I use any refractory granular material, for example aluminum oxide, silicon carbide, magnesia or any other suitable refractory 25 substance. This may be bonded together with ceramic bond and burned in a kiln, for example the plates may be manufactured in a kiln having flues which are the subject of the invention.

30 The muffle flues of the invention may be mounted upon plates or bricks 50 to raise them slightly from the ledges 25, and bricks 50 are spaced from each other along the length of the kiln so that air can find its way under the flues 35. 26. By reason of the fact that the amount of heat transmitted is proportional to the surface area to a considerable extent, there is more heat transmitted through my corrugated plates than through plane surface plates. At the same time 40 the corrugations and the construction described forms a stronger plate than a plane surface plate of the same cross section. These two features cooperate, for by reason of the greater strength and greater heat conduction, I may 45 embody the structure in a plate thinner than would otherwise be used and thus still further increase the conduction of heat without losing strength. Stating this in another manner, a certain minimum strength is required; this may be 50 achieved according to the present construction with a very thin plate which transmits more heat than would a thicker plate of the same strength and even more heat than would a plate of the same thickness but not corrugated.

55 The interlocking arrangement with the three T's is such as to form a very rigid structure and at the same time there is little danger of breakage in assembling owing to the fact that the plates can readily be pushed into position 60 in the T's. Still another feature of the invention resides in the fact that a mixture of re-

fractory granular material and bond can be pressed in a mold to great density. The shapes of the corrugated plates are such that no impediment is presented to molding with a mold the bottom of which represents one of the bevelled 5 edges of the plates and the top of which represents the other bevelled edge thereof. This permits tamping the material in the mold to form an extremely tough and strong plate. Furthermore, the T's may also be effectively molded. 10

Another feature of the invention resides in the fact that the triangular muffle flues disperse heat through the ware chamber 27 so as to give an even heating thereof. It will be noticed that the plates nearest the walls 28 radiate heat 15 outwardly to the walls 28 which is reflected upwardly to the arch 29. At the same time the plates 35 nearest the ware send heat directly onto the ware 33. A higher rate of convection will be achieved by reason of the fact that air 20 is drawn under the bottom plates 35. By the use of corrugated plates I also avoid too much concentration of radiated heat on one spot in the ware as it passes through the kiln.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth is to be interpreted as illustrative and not in a limiting 30 35 sense.

I claim:

1. In a muffle flue, three identical plates, three identical unions coterminous with the plates along the length of the flue and T shaped in cross section, said unions holding the plates together in the form of an equilateral triangle, each plate being corrugated with the corrugations extending perpendicular to the length of the flue. 40

2. In a muffle flue three identical corrugated 45 plates bevelled on the opposite edges of one side, said beveling being done at the ends of the corrugations, three identical junction pieces extending substantially the length of the plates and being T-shaped in cross section that is to say 50 having a central stem and top cross piece and two downwardly extending sides to the cross piece at an angle of approximately 30° to the cross piece, the bevelled ends of the plates abutting the central stem of the T and the side pieces 55 having corrugations matching the exterior of the plates, whereby the three plates are interlocked together in substantially gas tight condition, the corrugations extending perpendicular to the length of the flue. 60

CHARLES W. SAXE.
